UNITED STATES PATENT OFFICE.

JOHN VANDERKAMP, OF CLEVELAND, OHIO, ASSIGNOR, BY DIRECT AND MESNE ASSIGNMENTS, TO THE VAN TOY COMPANY, OF CLEVELAND, OHIO, A CORPORATION OF OHIO.

SOUND-REPRODUCING MACHINE.

Application filed September 10, 1921. Serial No. 499,744.

To all whom it may concern:

Be it known that I, JOHN VANDERKAMP, a citizen of the United States, residing at Cleveland, in the county of Cuyahoga and 5 State of Ohio, have invented certain new and useful Improvements in Sound-Reproducing Machines, of which the following is a specification.

This invention relates to sound reproducing machines, and the object of the invention is to provide an exceptionally simple machine adapted to be produced and sold as a toy at a relatively low cost and in which the amplifying horn is constructed in a particular way to support the tone needle and to reproduce sounds, using a disk record.

In the accompanying drawings, Fig. 1 is a plan view of my improved sound reproducing machine, and Fig. 2 is a horizontal 20 section of the body of the machine. Fig. 3 is a side elevation partly in section, of the machine. Fig. 4 is a horizontal sectional view of the sound reproducing or amplifying horn, on line 4—4 of Fig. 5, and Fig. 5 is a vertical sectional view longitudinally 25 of the horn. Fig. 6 is a cross section of a horn on line 6—6 of Fig. 5, showing the tone arm and needle. Fig. 7 is a reduced view 30 of the blank which is folded to provide the sound transmitting horn.

The invention comprises a relatively small box or cabinet 2 which is substantially square and formed with a wooden top and bottom 3 and 4, respectively, united together 35 at each corner by round wooden posts 5, and the four sides of the box are formed of a single sheet of relatively thin metal snugly sleeved over the corner posts. A crank shaft 6 for a wooden roller 7 extends through 40 openings in opposite sides of the box, the roller being located at one side of a vertical shaft 8 which is journaled centrally within the upper and lower wooden plates 3 and 4 respectively. Shaft 8 also comprises a 45 wooden roller, and an elastic band or belt 10 encircles the same and is driven by the crank roller 7. One or more elastic bands may be employed between said rollers.

The upper end of vertical shaft 8 projects 50 through top piece 3 and supports a relatively heavy metal disk 11 fastened to the shaft by heading the shaft, and the head 12 forms a projection centrally of the disk whereby a disk record 13 is adapted to be held in place 55 upon metal disk 11.

A round standard 14 extends upwardly from one corner of box 2 at one side of the periphery of disk 11, and a sound-reproducing and transmitting horn is adapted to be removably and rotatably engaged with the upper end of said post. Horn 15 is made of a single sheet of relatively stiff paper, fiber, or cardboard which is cut to provide an ar- 60 cuate or sector portion 16 and a straight tongue 17, and this blank is adapted to be folded on a straight radial line 18 to pro- 65 vide a horn of substantially semi-circular shape in cross section, one side being left substantially flat although also partly curved or bulging at a point intermediate its 70 ends where a curved tone arm 21 is inserted and affixed in place vertically through slots within the top and bottom sides of the curved wall at its tapering end. Tongue 17 is doubled back upon itself to provide 75 a round loop 22 normally oblong in cross section except when sleeved over round standard 14 upon which it fits with a slight friction but nevertheless sufficiently loose to turn upon the post. A small metal clip 80 23 fastens the folded end of tongue 17 where doubled back upon itself, and a straight metal binding strip 24 extends the full length of the base edge of the tongue and the blank and secures the abutting border 85 portions of the folded parts of the horn together. This strip also stiffens this portion of the horn, and the lower end of arm 21 projects through the curved side of the horn at one side of strip 24 where a needle 90 25 is adapted to be inserted in the tapering needle socket 26 which is formed at the extreme bottom end of the tone arm. The middle portion of the tone arm is in the form of a round hump 27 which is adapted 95 to bear against the rear wall 28 of the horn. This rear wall 28 is flat except when the tone arm is inserted to bear against it whereupon it is flexed slightly on curved lines at the smaller tapering end of the horn as seen 100 in Fig. 6. In operation when the crank of the machine is turned to rotate the record at a given speed the needle will impart its vibratory movement to the tone arm and to wall 28 of the horn, thereby reproducing the 105 sound recorded on the disk record and amplifying it also.

What I claim is:

1. A sound-reproducing machine, comprising a base in combination with a sound- 110

reproducing and amplifying horn mounted upon said base, a needle-supporting arm extending through said horn having a bulged portion in vibrating engagement with a portion of the wall thereof.

2. A sound-reproducing machine, comprising a base, a sound-reproducing horn of relatively stiff flexible material supported on said base, said horn having a normally flat wall, and a needle supporting arm extending through said horn having a lateral offset engaged with said wall of said horn and

adapted to maintain said wall in a flexed curved position.

3. A sound-reproducing and amplifying horn, made of relatively stiff and flexible material folded to a substantially semi-circular form and having a straight extension doubled back upon itself formed into a loop and a needle supporting arm extending through said horn having a curved portion intermediate its end engaged with one wall of said horn near its doubled extension.

JOHN VANDERKAMP.
